UNITED STATES PATENT OFFICE.

EDMUND L. AHERN, OF MOUNT GILEAD, OHIO.

BRACKET FOR SUPPORTING CLOSET TANKS.

Application filed June 20, 1922. Serial No. 569,764.

To all whom it may concern:

Be it known that I, EDMUND L. AHERN, a citizen of the United States, residing at Mount Gilead, in the county of Morrow and 5 State of Ohio, have invented certain new and useful Improvements in Brackets for Supporting Closet Tanks, of which the following is a specification.

The present invention relates to a bracket 10 for supporting a closet tank so that the majority of the weight will rest upon the bowl and has for its principal object to provide a device which may be readily assembled in conjunction with the bowl and tank.

15 A further object of the invention is to provide a bracket of this nature which will be efficient and simple in construction, reliable in operation, inexpensive to manufacture, durable, compact, neat in appearance, and 20 well adapted to the purpose for which it is designed.

With the above and numerous other objects in view as will appear as the description progresses, the invention resides in 25 certain novel features of construction, and the combination and arrangement of parts as will be hereinafter more fully described and claimed.

In the drawing:—

30 Figure 1 is a fragmentary elevation showing a bowl and tank with my invention associated therewith.

Figure 2 is a top plan of the bracket showing a portion of a toilet seat.

35 Figure 3 is a perspective of the forward portion of the bracket, and

Figure 4 is a detailed perspective of a bracket bar used in conjunction with the invention.

40 Referring to the drawing in detail it will be seen that 1 designates an ordinary toilet bowl which is provided in its upper surface with the holes indicated by the dotted lines at 2 for receiving the hinge posts 3 which

45 support the seat and cover. My bracket consists of the hole engaging member indicated generally at 4 which includes a pair of spaced bracket arms 5 having formed at their lower ends the apertured ears 6 reg-

50 istering with the depending sleeves 7 which are adapted to be positioned in the holes 2 of the bowl 1. The upper end of these bracket arms 5 terminate in the sleeves 8. The sleeves 8 and the ears 6 are adapted to

extend in horizontal planes whereas the 55 arms 5 slant upwardly from the ears 6 to the sleeves 8. A brace bar 9 connects the arms 5 intermediate their ends preferably adjacent the sleeves 8. A pair of bracket bars 10 are fixed to the wall 11 behind the 60 bowl 1 being provided with suitable apertures 12 for receiving screws or other retaining elements. An offset extension 13 is provided at the upper end of each bracket bar 10 and is pierced longitudinally so as to 65 provide the hole 15. A pair of rods 16 have their ends positioned in the sleeves 8 and the holes 15 of the offset projection 13 so that they will lie horizontally for supporting the closet tank 17. It will thus be seen 70 that the majority of the weight of the tank will be rested upon the bowl 1 through the intermediacy of the bracket just described. The bowl engaging members 4 and the bracket bars 10 may be made in standard 75 sizes and the rods 16 can readily be cut during the assembly of the bowl and tank depending upon the distance between the bowl and the wall.

Where the wall 11 is provided with tiles it 80 is preferable to provide certain of the tiles with openings for receiving the rods 16 rather than fix the bracket bars 10 to the wall.

It is thought that the construction, utility 85 and advantages of the bracket will now be readily understood without a more detailed description. The embodiment of the invention which I have described with some degree of particularity, however, merely refers to 90 the preferred construction and it is to be understood that numerous changes in form, in the details of construction and in the combination and arrangement of parts may be resorted to without departing from 95 the spirit of the invention as hereinafter claimed.

Having thus described my invention what I claim as new is:—

1. In combination, a toilet bowl, a toilet tank, and a bracket disposed between the tank and the bowl, said bracket including a pair of bracket arms having their lower ends supported on the bowl, a pair of rods having one end supported in the bracket 100 arms and means at their other ends for support.

2. In combination, a toilet bowl provided

with holes in its upper edge, a pair of bracket arms having one of their ends projecting in said holes and their other ends terminating in sleeves, a pair of rods having one end disposed in said sleeves, means at the other end of the rods for supporting them and a tank resting on the rods.

In testimony whereof I affix my signature in presence of two witnesses.

EDMUND L. AHERN.
